COMBINED KNOB AND ROSE FOR A DOOR LOCK

Andrea Spadini, Rome, Italy

Application June 15, 1956, Serial No. 41,915

Term of patent 7 years

(Cl. D50—3)

Fig. 1.

Fig. 2.

Fig. 1 is an end view of a combined knob and rose for a door lock embodying my new design. Fig. 2 is a bottom view showing the combined knob and rose.

I claim:

The ornamental design for a combined knob and rose for a door lock, substantially as shown.
